Primary Examiner — S. Bryan Reinholdt, Jr.(74) *Attorney, Agent, or Firm* — Michael Bartholomew(57) **CLAIM**

The ornamental design for a cup lid, as shown and described.

DESCRIPTION

FIG. 1 is a bottom, front, and right side perspective view of a cup lid, showing my new design;

FIG. 2 is a top, rear, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, shown in a condition of use; and,

FIG. 10 is an enlarged view of a portion labelled 10 in FIG. 9.

The broken lines in the drawings depict portions of the cup lid that form no part of the claimed design. The dash dot dash lines in FIG. 9 and FIG. 10 are for the purpose of depicting the boundary of the enlarged view and form no part of the claim. The broken lines in FIG. 9 depicting the environment of a bottle form no part of the claimed design.

1 Claim, 10 Drawing Sheets(56)
